FEEDER FOR BUCKET ELEVATORS

Pierre Diebold, Nancy, France

Application May 17, 1947, Serial No. 748,834
In France February 22, 1945Section 1, Public Law, 690, August 8, 1946
Patent expires February 22, 1965

6 Claims. (Cl. 198—55)

1

The present invention has for its object improvements in continuously operating elevators for pulverulent and the like materials, such as grains and the like, with a view to increasing their output through an increase in speed and on the other hand to avoid any clogging at the lower end of such an apparatus and the objectionable results of such clogging.

It is a well known fact that the clogging in such apparatus is due to the accumulation of material in the lower or foot end of the casing of the elevator.

This accumulation may be produced either through an excess admission of the products at the lower end of the elevator or through the return, inside the elevator frame, of the products projected against the walls of the head of the elevator and not removed through the output port.

According to the invention, the first drawback is removed and the speed and the consequent output of the elevator is increased by feeding the apparatus not at the lower drum but at the rising part of the elevator. For this purpose there is provided in front of the rising side of the elevator a suitably shaped input pipe opening into said elevator for pouring the desired products into the buckets of the elevator conveyor. To the rear of the rising side of the elevator is located a barrier plate adapted to stop the projection of the products. Preferably, said barrier plate is made of two parts, one of which is stationary and the other of which is movable with the lower drum or toothed wheel. The latter is closed and its lateral walls are smooth and of flat, conical, or dome shape.

To remove the second above-mentioned drawback, i. e., the return movement of the product, the upper drum or pinion is constructed in the same manner as the lower pinion, and it rotates inside the opening of a barrier plate on which the raised material falls and is guided to the exhaust port.

The invention is illustrated by way of example, and by no means in a limiting sense, in the accompanying drawings showing diagrammatically, in Fig. 1 a vertical cross-section of an embodiment of the invention, and in Figs. 2 and 3 cross-sections through lines 2—2 and 3—3 of Fig. 1, respectively.

The drawing shows an elevator constituted by conveyor belts or chains carrying buckets 2 passing over a lower or foot drum 3 and over a head or higher drum 4, said drums rotating respectively on shafts 5 and 6 and the whole arrangement being located inside a fluid-tight casing 9.

The products or material to be raised are

2

brought through a pipe or channel 7 ending with a spout so as to define the passageway for the product towards the buckets 2 or else towards the useful zone of the felt if no such buckets are extant.

To stop the particles of material which do not fall into the buckets, there is provided behind the rising conveyor side a barrier plate means constituted by two elements. One barrier plate element 8 is rigid with the frame of the elevator, while the other 9 is movable with the lower drum shaft 5. For instance, the barrier plate 9 may be carried by two arms 10 joined to the bushings of the spindle 5. Through this arrangement, the lower drum or pinion may move by gravity to give the chains or belts of the elevator the required tension. Any suitable guides may be provided for the shaft 5 and arms 10.

The lower drum is a closed structure. It includes a rim 11 as shown in Fig. 2, possibly with one or more series of teeth 12 and two side flanges 13 that are flat, conical, or slightly dome-shaped.

The barrier plate 8 encloses the lower drum with as little clearance as possible, and it may be formed with yielding tongues or brushes 14 so as to remove this clearance entirely.

The barrier plate 9 may be provided with similar tongues.

With a view to doing away with the return of the products from the top of the apparatus, the upper or head drum 4 is constructed in the same manner as the lower or foot drum 3.

Drum 4 is provided with flanges 15 that may be flat, conical or dome-shaped (Fig. 3) and it rotates between the edges of an opening in the inclined barrier plate 16 (Fig. 1), the slope of which provides for normal removal of the material directed by said slope towards the outlet 17.

The barrier plate 16 may be provided with yielding tongues or brushes 18 adapted to eliminate any clearance around the drum.

Through such an arrangement, it is possible to maintain the lower drum of the elevator completely free while removing, almost completely, the pulverulent or like material to be raised.

It should be noted, moreover, that the improved arrangement removes the drawbacks inherent in the centrifugal force that conflicts with the filling of the buckets when the material is introduced into the bottom of the elevator.

I claim:

1. An elevator comprising, in combination, a casing; endless conveyor means mounted in said casing for movement with one side thereof upwardly along said casing and for movement with

the other side thereof downwardly along said casing; an upper drum and a lower drum respectively mounted for rotation in upper and lower parts of said casing and within upper and lower parts of said endless conveyor means so as to guide the same in said casing, said lower drum resting on said lower part of said endless conveyor means and being connected to bearings which are freely mounted in said casing so that said lower drum moves downwardly in said casing as said endless conveyor means becomes elongated after a period of usage; and barrier plate means fixedly connected to said bearings, enclosing the sides and an upper part of said lower drum, and being located just behind said one side of said conveyor means, whereby said barrier plate means prevents any material falling from said conveyor means from clogging the rotation of said lower drum and whereby said barrier plate means is movable with said lower drum when said conveyor means becomes elongated.

2. An elevator comprising, in combination, a casing; endless conveyor means mounted in said casing for movement with one side thereof upwardly along said casing and for movement with the other side thereof downwardly along said casing; an upper drum and a lower drum respectively mounted for rotation in upper and lower parts of said casing and within upper and lower parts of said endless conveyor means so as to guide the same in said casing, said lower drum resting on said lower part of said endless conveyor means and being connected to bearings which are freely mounted in said casing so that said lower drum moves downwardly in said casing as said endless conveyor means becomes elongated after a period of usage; first barrier plate means fixedly connected to said bearings, enclosing the sides and an upper part of said lower drum, and being located just behind said one side of said conveyor means, whereby said first barrier plate means prevents any material falling from said conveyor means from clogging the rotation of said lower drum and whereby said first barrier plate means is movable with said lower drum when said conveyor means becomes elongated; and second barrier plate means fixedly connected to said casing and also located just behind said one side of said conveyor means, said second barrier plate means having a lower edge located in overlapping relationship with an upper portion of said first barrier plate means, whereby said first and second barrier plate means present a continuous surface for deflecting any falling material from said lower drum.

3. An elevator comprising, in combination, a casing; endless conveyor means mounted in said casing for movement with one side thereof upwardly along said casing and for movement with the other side thereof downwardly along said casing; an upper drum and a lower drum respectively mounted for rotation in upper and lower parts of said casing and within upper and lower parts of said endless conveyor means so as to guide the same in said casing, said lower drum resting on said lower part of said endless conveyor means and being connected to bearings which are freely mounted in said casing so that said lower drum moves downwardly in said casing as said endless conveyor means becomes elongated after a period of usage; first barrier plate means fixedly connected to said bearings, enclosing the sides and an upper part of said lower drum, and being located just behind said one side of said conveyor means, whereby said first barrier plate means prevents any material fall-

ing from said conveyor means from clogging the rotation of said lower drum and whereby said first barrier plate means is movable with said lower drum when said conveyor means becomes elongated; second barrier plate means fixedly connected to said casing and also located just behind said one side of said conveyor means, said second barrier plate means having a lower edge located in overlapping relationship with an upper portion of said first barrier plate means, whereby said first and second barrier plate means present a continuous surface for deflecting any falling material from said lower drum; and a supply chute mounted on said casing in substantially spaced relation to the lowermost part of said conveyor means and terminating adjacent to said one side of said conveyor means.

4. An elevator comprising, in combination, a casing; endless conveyor means mounted in said casing for movement with one side thereof upwardly along said casing and for movement with the other side thereof downwardly along said casing; an upper drum and a lower drum respectively mounted for rotation in upper and lower parts of said casing and within upper and lower parts of said endless conveyor means so as to guide the same in said casing, said lower drum resting on said lower part of said endless conveyor means and being connected to bearings which are freely mounted in said casing so that said lower drum moves downwardly in said casing as said endless conveyor means becomes elongated after a period of usage; first barrier plate means fixedly connected to said bearings, enclosing the sides and an upper part of said lower drum, and being located just behind said one side of said conveyor means, whereby said first barrier plate means prevents any material falling from said conveyor means from clogging the rotation of said lower drum and whereby said first barrier plate means is movable with said lower drum when said conveyor means becomes elongated; second barrier plate means fixedly connected to said casing and also located just behind said one side of said conveyor means, said second barrier plate means having a lower edge located in overlapping relationship with an upper portion of said first barrier plate means, whereby said first and second barrier plate means present a continuous surface for deflecting any falling material from said lower drum; a supply chute mounted on said casing in substantially spaced relation to the lowermost part of said conveyor means and terminating adjacent to said one side of said conveyor means; a discharge chute located adjacent to an upper part of said conveyor means; and inclined barrier plate means located about said upper drum and communicating with said discharge chute so as to direct material falling from said conveyor means to said discharge chute.

5. An elevator, comprising, in combination, a casing; endless conveyor means mounted in said casing for movement with one side thereof upwardly along said casing and for movement with the other side thereof downwardly along said casing; an upper drum and a lower drum respectively mounted for rotation in upper and lower parts of said casing and within upper and lower parts of said endless conveyor means so as to guide the same in said casing, said drums each being substantially cylindrical and having opposite closed ends, said lower drum resting on said lower part of said endless conveyor means and being connected to bearings which are freely mounted in said casing so that said lower drum

moves downwardly in said casing as said endless conveyor means becomes elongated after a period of usage; first barrier plate means fixedly connected to said bearings, enclosing the sides and an upper part of said lower drum, and being located just behind said one side of said conveyor means, whereby said first barrier plate means prevents any material falling from said conveyor means from clogging the rotation of said lower drum and whereby said first barrier plate means is movable with said lower drum when said conveyor means becomes elongated; second barrier plate means fixedly connected to said casing and also located just behind said one side of said conveyor means, said second barrier plate means having a lower edge located in overlapping relationship with an upper portion of said first barrier plate means, whereby said first and second barrier plate means present a continuous surface for deflecting any falling material from said lower drum; a supply chute mounted on said casing in substantially spaced relation to the lowermost part of said conveyor means and terminating adjacent to said one side of said conveyor means; a discharge chute located adjacent to an upper part of said conveyor means; inclined barrier plate means located about said upper drum and communicating with said discharge chute so as to direct material falling from said conveyor means to said discharge chute; and brush means respectively mounted between said first and inclined barrier plate means and said drum ends of said upper and lower drums and contacting said drum ends so as to seal said drums from material falling from said conveyor means.

6. An elevator, comprising, in combination, a casing having a bottom wall; endless conveyor means having a lowermost part substantially spaced from said bottom wall, including a plurality of spaced buckets, and being mounted in said casing for movement with one side thereof upwardly along said casing and for movement with the other side thereof downwardly along said casing, whereby said buckets may scoop up material which accumulates on said bottom wall of said casing; an upper drum and a lower drum respectively mounted for rotation in upper and lower parts of said casing and within upper and lower parts of said endless conveyor means so as to guide the same in said casing, said drums each being substantially cylindrical and having opposite closed ends, said lower drum resting on said lower part of said endless conveyor means

and being connected to bearings which are freely mounted in said casing so that said lower drum moves downwardly in said casing as said endless conveyor means becomes elongated after a period of usage; first barrier plate means fixedly connected to said bearings, enclosing the sides and an upper part of said lower drum, and being located just behind said one side of said conveyor means, whereby said first barrier plate means prevents any material falling from said conveyor means from clogging the rotation of said lower drum and whereby said first barrier plate means is movable with said lower drum when said conveyor means becomes elongated; second barrier plate means fixedly connected to said casing and also located just behind said one side of said conveyor means, said second barrier plate means having a lower edge located in overlapping relationship with an upper portion of said first barrier plate means, whereby said first and second barrier plate means present a continuous surface for deflecting any falling material from said lower drum; a supply chute mounted on said casing in substantially spaced relation to the lowermost part of said conveyor means and terminating adjacent to said one side of said conveyor means; a discharge chute located adjacent to an upper part of said conveyor means; inclined barrier plate means located about said upper drum and communicating with said discharge chute so as to direct material falling from said conveyor means to said discharge chute; and brush means respectively mounted between said first and inclined barrier plate means and said drum ends of said upper and lower drums and contacting said drum ends so as to seal said drums from material falling from said conveyor means.
